TWEEZER

Samuel Segal, Brooklyn, N. Y.

Application January 4, 1933, Serial No. 650,194

24 Claims. (Cl. 128—354)

The subject matter of this invention is generally concerned with gripping and extracting instruments and more particularly is directed to a manually controlled double wing self releasing tweezer for extracting hair.

In the performance of tweezers of the character referred to, it is very desirable to maintain sufficient pressure on the hair gripping and extracting jaws during their rearward extracting stroke upon the manipulation of the arms or wings of the tweezers. In practice however it has been found that the pressure of the gripping jaws on a hair to be extracted was practically at a maximum only at the beginning of their rearward stroke. After the beginning or during the rearward stroke of the jaws, the holding pressure on the hair gripping surfaces thereof lessened with the result that the initial grip on the hair to be extracted became correspondingly less as the extracting stroke progressed such that although the jaws were moving rearwardly to extract the hair, the jaws failed to effectively hold and grip the hair. With this difficulty experienced, the hair to which the tweezer was applied would not be extracted due to the ineffective gripping as a result of slippage of the tweezer jaws over the hair. It is therefore a particular object of the invention to provide an improved tweezer or manually actuated instrument in which the jaws are maintained at an effective gripping pressure throughout their rearward and complete extracting stroke to prevent slippage of jaws over the hair to which the tweezer is applied.

Other objects, advantages and features of my invention and discovery appear from the accompanying drawings, the subjoined description and the appended claims.

In the drawings which illustrate several embodiments of the invention.

Fig. 1 is a front elevational view of the tweezer according to the invention illustrated partly in section and expanded; Fig. 2 is a view closely similar to Fig. 1 showing the tweezer collapsed; Fig. 3 is a section across the line 3—3 of Fig. 1; Fig. 4 is a section on the line 4—4 of Fig. 2; Fig. 5 is a section on line 5—5 of Fig. 1; Fig. 6 is a fragmentary view in perspective of an upper portion of a manipulating wing or arm of the tweezer.

Fig. 7 is an elevational view of a tweezer showing the retainer disposed within the cylindrical guide for the jaws depressed preparatory to the insertion and locking of the upper portion of the wings within openings or sockets at the upper

end of the guide; Fig. 8 is a fragmentary view in elevation of a tweezer according to the earlier illustrations, but including an adjustable member for regulating the tension of the pressure spring disposed between the upper portion of the jaws and the wings.

Fig. 9 shows an elevational view and in part in section of a tweezer having the pressure springs disposed obliquely with respect to the jaws and wings; Fig. 10 is a fragmentary view of a tweezer 10 showing a modified construction in which pressure is applied to the sides of the jaws by the assistance of a U shaped spring; Fig. 11 shows a fragmentary portion of a tweezer in which the companion jaws are provided with disc shaped 15 members to aid the gripping of the hair and to facilitate the discharge after extraction; Fig. 12 is a fragmentary enlarged view, partly in section, of the lower portion of the jaws shown in Fig. 11; Fig. 13 is a view taken on the line 13—13 20 in Fig. 12; Fig. 14 is a view similar to Fig. 12 but illustrating a modified form of hair gripping disc; Fig. 15 is a view taken on the line 15—15 in Fig. 14.

Fig. 16 illustrates a vertical elevation, partly 25 in section, of a modified tweezer showing the adjustable stud within the guide in an extreme lowered position to permit the maximum retraction of the jaws; Fig. 17 is a view similar to Fig. 16 but with the stud adjusted to an opposite 30 extreme position to prevent retraction of the jaws; Fig. 18 is a section across the line 18—18 of Fig. 16; Fig. 19 is a section on the line 19—19 of Fig. 16 and; Fig. 20 is a vertical elevation of a 35 tweezer according to the form illustrated in Fig. 16 but including springs interposed between the jaws and wings to provide automatic side pressure to the jaws on the extracting stroke.

The gripping and extracting device or tweezer instrument according to a specific embodiment 40 of the invention includes a pair of elongated jaws, the lower operating faces at one end thereof may be flattened and/or corrugated to form gripping faces to effectively hold the hair to be extracted; and the other end of the jaws are so 45 provided with correlated recesses, projections and shoulders and positioned inside of a cylindrical guide that an effective pivotal connection is formed therebetween. Symmetrically attached to the sides of the jaws by pivoted links and in 50 slots or sockets in the upper part of the cylindrical guide by elongated recessed and grooved laterally arranged knobs or flanges are a pair of wings or arms to be gripped by the hand in actuating the device. Disposed within the cy- 55

lindrical guide is positioned a helicoidal spring on which is seated a cylindrical plug or retainer which cooperates with the recesses of the lateral disposed flanges for locking them in position and with the jaws to normally hold them spread apart.

In one embodiment, side pressure is normally exerted on the jaws of the tweezer by a pair of laterally extending springs having their inner ends passing through a perforation in the cylindrical guide and bearing against adjacent upper portion of the jaws while the outer portions of the spring are suitably mounted on the inner faces of the wings of the tweezer.

In another embodiment of the invention provision has been made for regulating the pressure of the springs between the tweezer jaws and the wings thereof and for this purpose a thumb screw member in the form of wheel is threadably mounted on a stud or projection associated with the arms of the tweezer for either adjustably increasing or lessening the tension of a respective spring.

In carrying the invention into effect the pressure springs interconnecting the arms and jaws of the tweezers, provide a certain force against the sides of the jaws to effectively hold the hair gripping faces against the hair to be extracted on the extracting stroke of the jaws and the pressure springs may be interconnected between the arms and jaws of the tweezer as to be substantially horizontal according to the invention or the same effect may be produced by arranging the pressure springs obliquely with respect to the jaws and arms.

In the preferred embodiment of the invention, provision has been made for regulating the extracting stroke of the jaws in utilizing an adjustable and rotatable guide sleeve in which the pivotal joint of the jaws are housed, which sleeve upon rotation controls the elevation of an adjustable member connected to one of the jaws to limit their rearward movement and the adjustable member cooperates with suitable spring means whereby varying degrees of pressure may be transmitted to the jaws for their separation.

Referring now to the drawings, the tweezer instrument as shown in the several views is provided with a pair of elongated substantially semi cylindrical jaws 10 and 11 having hair gripping and extracting faces 12 and 13 which may be suitably roughened, smoothed or corrugated and extend beyond the respective rectilinear inner faces 14 and 15. The other ends of the jaws are retained inside of the cylindrical sleeve or guide 16 and their contracting faces are so constituted as to form a pivotal connection therebetween. In forming this pivotal connection, jaw 10 is provided with a channel 17 to receive the elongated boss or ridge 18 of the jaw 11.

Sides 19 of the channel 17 project beyond the rectilinear face 14 to form a shoulder 20 which cooperates with the shoulder 21 formed by the depression 22 above face 15. The bottom face 23 of the cylindrical end 24 of jaw 11 serves as a stop for the sloping end 25 of jaw 10.

The upper end of the sleeve 16 is closed as indicated at 26 and is provided with an integral knob 27 having a central opening or bore 28. Suitably retained in the sleeve 16 between the cylinder or plug 29 and the cylindrical end portion 24 of jaw 11 is a helicoidal spring 30 for normally pressing the jaws forwardly and keeping the instrument in expanded position as shown in Fig. 1 and for retaining the tweezer

arms hereinafter referred to, locked in the sleeve.

The outer faces of the guide sleeve 16 just below the spheroidal shaped knob 27 are flat and the adjacent faces are preferably at right angles to each other, that is, the upper end of the sleeve is squared and is provided with two symmetrical transverse sockets or grooves 31 which serve as fulcrums for and receive the lateral and inwardly disposed flanges 32 of wings 33.

The flanges 32 are provided with a centrally arranged recess 34 having curved surfaces 35 to partly encircle the sides of the retainer or cylindrical plug 29 and the latter locks the wings 33 in position in the sockets 31 and prevents disengagement of the flanges 32 from the squared portion of the guide or sleeve.

The overhanging lips or edges 36 of the sockets 31 cooperate with the transversely disposed grooves 37 on the upper part of the flanges 32 whereby the upper portion of the arms or wings 33 are retained in the sockets and consequently lateral slippage of the arms 33 is prevented.

The outer faces of the wings 33 are desirably embellished or decorated as is also the outside of the guide 16 and the lower portions of the wings are suitably flattened or ridged to form grips in any appropriate manner.

The inner faces of wings 33 and the outer faces of jaws 10 and 11 are provided with ears 38 and 39 respectively in which (see also Fig. 4) are press fitted the pivot pins 40, the ends 41 of which are of reduced diameter and receive the sides of the U shaped channel link 42, the channel portion facing downwardly and forwardly.

According to the invention, the upper closed face of the link 42 upon collapsing of the tweezer instrument is stopped by the extension 44 of the projecting ears 38 (see Fig. 2).

In expanded position of the tweezer the terminal 45 of the links 42 will be stopped by the ears 39 of the jaws as shown in Fig. 1. In assembling, the sides of the channel link 42 may be pressed into the reduced ends 41 of the pivot pins 40 and if desired the free terminals of the reduced ends may be upset although in actual practice it has been found that upsetting is not necessary.

With the present arrangement, there is no possibility of injuring the hand or face of the operator due to pinching when using the tweezer. Heretofore, the link members 42 were reversed and had their channels facing upwardly and rearwardly. In Fig. 2, the gap portions shown between the ear 39 and terminal 45, formerly appeared between the ear 38 and the adjacent terminal of the link. With the tweezer collapsed as in Fig. 2, and the link members reversed as to have their channels facing upwardly and rearwardly, the gap which formerly appeared between the ear 38 and the adjacent terminal of the link formed in effect a miniature tweezer which tended at times to catch the flesh of the user. It has been found that by reversing and inverting the channel links to face downwardly and forwardly the miniature tweezer is formed by the terminals 45 and ear 39 where it can do no harm or injury.

In assembling the tweezer instrument, the jaws and arms are first interconnected by the channel shaped links. Subsequently the jaws 10 and 11 are placed together so that the boss 18 will fit into recess 17 and the shoulders 20 and 21 contact. The cylindrical plug or retainer 29 is placed within the bore of the guide 16. The helicoidal spring 30 is then inserted in the guide. Following this, the upper portions of the

jaws 10 and 11 are arranged within the lower part of the tubular guide. With the cylindrical plug 29 against the top inner face of the squared portion and the springs 30 disposed between the 5 plug and the jaw 11 in such fashion as to be under no compression, the upper portions of the arms are below the sockets of the guide. In order that the upper portions of the arms may be raised to the elevation of the sockets, 10 spring 30 must be compressed or made shorter. This is accomplished by positioning the bore of the knob 27 on a fixed extension 45 mounted on wall 46 (see Fig. 7). The extension 45 may be in the form of a short rod and forms no part of 15 the tweezer instrument.

With the rod 45 against the cylindrical retainer 29 the wings of the tweezer are bodily moved rearwardly against the energy of spring 30. This causes the retainer to move away from 20 the top inner face of the squared portion and also aids to compress the spring. If the spring be compressed the upper portions of the tweezer arms may be extended to interlock with the guide. Thus the flanges of the jaws may be 25 brought to the elevation of the sockets 31 in which they are slipped. The tweezer instrument is then removed from the fixed extension 45 and thus the spring 30 automatically expands. Consequently the cylindrical plug passes into the 30 curved recesses 34 of the flanges 32 and locks the latter against transverse slippage. Downward pressure by the spring on cylindrical part 24 of jaw 11 causes the hair gripping and extracting portions 12 and 13 of the jaws to be 35 normally spread apart.

To dismantle the instrument, if assembled, rod 45 is inserted in the bore of the knob 27 to press down the locking plug below the recesses 34 whereupon the flanges 32 may be slipped out of 40 the sockets 31. Then the wings 31 with linked jaws may be removed from the guide, as may also be helicoidal spring 30 and the locking plug.

In operation, the wings 22 of the tweezer may be gripped at 47 between the fingers, preferably 45 the thumb and index finger of the right or left hand at substantially any angle. Upon compression, that is upon the movement of the jaws toward each other, the first step of the movement of the arms will bring the gripping extracting faces 12 and 13 of the jaws together. This position may be considered as the initial 50 clamping or gripping position of the tweezer. In this position the gripping and extracting faces are against a hair to be extracted. To extract a hair to which the tweezer has been applied, it is necessary that the jaws be moved 55 rearwardly. This stroke is caused on the second step of the movement of the wings in the direction towards each other. However, it is also 60 essential that the initial grip on the hair by faces 12 and 13 be maintained or increased during the extracting stroke of the jaws. For this purpose and to insure that the faces 12 and 13 hold the hair without slippage, supplementary 65 pressure is provided on the sides of the tweezer jaws. In the preferred form of the invention, the side pressure is supplied by interconnecting the wings and the upper portion of the jaws with suitable helicoidal springs 50. For example, 70 in the form shown in Figs. 1 and 2, springs 50 are substantially horizontal that is approximately at ninety degrees with respect to the axis of the tubular guide. In the form according to Fig. 9, pressure springs 50 connected to the jaws 75 and arms of the tweezer are approximately at

an angle of forty five degrees with the tweezer expanded. In the case of the form illustrated Figs. 1 and 2 the outer ends of the springs 50 are removably mounted on a stud 51 on the inside of the arms or wings and the inner ends 5 are disconnectably mounted on the shank 52 underneath the head of a button 53 which bears against the sides of the jaws and is removably disposed within an opening as 54 at the lower part of the tubular guide.

With regard to the springs 50 shown in Fig. 9 their outer ends are removably mounted on posts 51 carried by the arms and their inner ends are appropriately, in similar fashion, disconnectably arranged on studs or posts 55 carried by the 10 jaws.

With the tweezer jaws brought merely together such that the gripping and extracting faces 12 and 13 initially clamp a hair to be extracted, no effective side pressure is created by 20 the laterally disposed springs 50. Upon further manipulation of the wings effective side pressure is brought about due to the compression of the springs 50 as the rearward stroke of the jaws commences and progressively increases until the 25 rearward stroke concludes. It is thus apparent that the grip on the hair by the faces 12 and 13 is intensified due to the gradual increase of compression of the lateral springs 50 during the extracting stroke of the jaws. Hence the grip 30 on a hair by the jaws will be sustained and consequently preclude slippage of the jaws over the hair. With the hair firmly clamped on the rearward stroke, the hair pulls away from the flesh and at the completion of this stroke and the 35 tweezer takes the form shown in Fig. 2, namely collapsed.

If the side pressure applied by the operator be now removed from the actuating surfaces 47, the jaws move forwardly by reason of the action of 40 spring 30 and consequently separate with the result that the hair formerly withdrawn from the flesh is discarded. On the return of the jaws to normal the lateral springs 50 expand as is the case also of the more powerful helicoidal 45 spring 30.

It has been discovered that with the lateral springs disposed between the jaws and wings, the tweezer operates in a relatively silent fashion doing practically away with the objectionable clicking between the links, the extensions 50 44, and ears 39. The clicking action formerly developed with tweezers of the character referred to which did not utilize side springs is now substantially absorbed or cushioned by the 55 compensating springs 50.

In the form of the invention according to Fig. 8, provision has been made for adjusting or regulating the tension of the side springs 50. To this end, stud 51 is threaded and cooperates 60 with a knurled threaded disc wheel 60 and the latter may be shifted along the stud to regulate the spring to the desired pressure.

According to the form illustrated in Fig. 10, the pressure is applied to the jaws by the aid of 65 an inverted U shaped flat spring 61 disposed in a correspondingly shaped groove formed at the upper part of the jaws, the spring 61 having perforated terminals threadably engaging a shank of a set screw 62. Pressure of the sides of 70 the jaws may be regulated by adjusting set screws 62.

If desired, the gripping and extracting faces of the tweezers may take the form of discs as 75 appropriately mounted at the lower portion 75

of the jaws. More specifically however extending from each disc is a shank 71 which is freely and rotatably disposed in a perforation at the lower portion of a jaw. Although the discs are preferably rotatably secured to the jaws, if desired they may be firmly secured thereto in any suitable manner. To facilitate the holding action of the discs, they include a dished surface 72 of the type shown in Figs. 12 and 13 or they 10 may be provided with a corrugated surface as shown in Figs. 14 and 15. For convenience in removing a hair in the event it sticks to a gripping and extracting jaw after a full cycle of the tweezer has been completed, namely after a 15 rearward extracting stroke, the disc to which the hair is sustained may be rotated and this action separates and discards the hair therefrom.

In the case of the preferred embodiments illustrated in Figs. 16 to 20 inclusive, the cylindrical sleeve or guide 80 and the squared head or member 81 are made in two separate parts. Head 81 includes a longitudinal channel or bore 82 which receives the helicoidal spring 83, the 25 terminals of which overhang opposite sides of the head and normally abut the upper portions of the arms or wings 33 of the tweezer, which arms are appropriately pivotally connected to the upper portion of the head by suitable pivots 30 84. Head 81 is provided with an integral and spheroidal shaped terminal 85. From the lower horizontal face 86 of the head integrally depends the axially arranged cylindrical post 87 having a bottom flat face 88. The lower face 86 of 35 the head 81 is also provided with opposed detents or small projections 89 for a purpose hereinafter described.

The cylindrical sleeve or guide 80 in which the pivotal connection formed at the upper end 40 of the jaws 10 and 11 is housed comprises a shell or casing having a top wall 90 including a concentric opening 91 in which the depending post 87 of the head 81 is removably received. The inner face of the sleeve is provided 45 with the opposed and aligned guide slots 92 and 93 extending substantially the entire height thereof, which slots guide the reduced terminals of a pin 94 loosely carried by and at the lower part of the head 95 of an adjustable stud generally designated 96, the threaded shank 97 of 50 which is threadably interconnected in the threaded bore 98 of the boss or lug 18 at the upper part of jaw 11, the boss being disposed in a suitable elongated recess 17, which in association with cooperating shoulders as 20 and 21 55 of the type described in connection with Figs. 5 provide the pivotal joint between the jaws 10 and 11.

A helicoidal vertically disposed spring 99 has 60 its lower end seated on the overhanging portions of the pin 94 and surrounds a major portion of the head of the stud 96. The upper end of spring 99 surrounds the depending post or extension 87 and abuts the inside face of the top wall 90 of the sleeve. Hence, spring 90 has a double function, to wit, first in urging the top wall of the guide sleeve against the lower face of the head 81 and secondly in imparting a downward force against the lateral flange 100 65 overhanging the upper part of the jaw 11 for normally separating the lower gripping faces of the jaws.

Since the spring supporting pin 94 is non rotatably guided in the vertical sleeve 80, rotation 70 of the sleeve will accordingly bodily carry

the pin 94 with it. Consequently, if the sleeve be rotated relative to the post 87 and the pivotally connected jaws, the threaded shank will be rotated and thus, either increase or decrease the distance between head of adjustable stud 96 and the bottom part of the post 87 depending upon the direction of rotation of the sleeve. 5

As illustrated in Fig. 16, the shank 98 occupies substantially the entire length of the internally threaded bore 89 of boss 18 and the pin 10 94 is disposed adjacent the overhanging flange 100 which acts as a stop and limits the downward movement of the head 95. In such, position of shank 98, the vertical spring 99, as confined within the sleeve is under least compression. Hence less downward pressure is transmitted for the separation of the jaws. It follows therefore that less pressure need be applied to the jaws for their separation. Correspondingly less pressure is necessary on the part 20 of the operator in the manipulating of the wings for retraction of the jaws. In the position of the shank 98 as illustrated in Fig. 16, the distance between the head 96 thereof and the post 87 is the equivalent to their largest distance of separation, or equivalent to the longest rearward stroke of the jaws under the least opposing spring pressure by the helicoidal spring 99. 15

According to the forms of the invention shown 30 in Figs. 16 and 20, links 101 have their ends pivotally connected to the inside of the bottom parts of wings 33 and to suitable lugs 102 carried by the jaws. If therefore the wings be brought in a direction towards each other, the 35 links operate to simultaneously retract both of the jaws. On the completion of the rearward stroke, spring 99 automatically operates when finger pressure is removed from the wings to move the jaws forwardly and apart. 40

The wings are also normally urged outwardly by reason of spring 83 which became contracted on the movement of the wings towards each other and automatically expands upon release of finger pressure from the wings. 45

With the sleeve and stud adjusted for the longest rearward stroke of the tweezer, as in Fig. 16, hairs offering little resistance to extraction may be quickly pulled out. If hairs offer more resistance a greater pressure may be applied to the pivotal connection of the jaws. This is accomplished by grasping the knurled portion 103 of the sleeve and rotating the latter about post 87 in a proper direction so as to raise the threaded shank 97 with respect to its boss such 50 that the distance between the head of stud 96 and post 87 is decreased and thus compressing the helicoidal spring 99. Consequently, added finger pressure on the wings is necessary on the part of the operator to overcome the increased 55 spring pressure on the jaws. This extra pressure applied to the wings overcomes the added resistance to extraction offered by the hairs and also prevents slippage of the hair between the clamping and extracting faces of the jaws during the latter's retraction. In a similar fashion the sleeve and jaws may be adjusted and set for hairs offering various degrees of resistance for 60 their extraction. 65

As illustrated in Fig. 17, the sleeve has been 70 rotated as to arrange a major portion of the threaded shank 97 above the overhanging flange 100. In this position, it will be noted that the head 95 of the stud 96 is against the stop projection 87 and the spring 99 is completely com- 75

pressed. Therefore there is no gap between the head 95 and the projection 87. It follows that although the wings 33 may be manipulated as to bring the lower portions of the jaws towards each other to grip a hair nevertheless it will be impossible to slidably shift the jaws rearwardly relative to the guide sleeve. In this case, to extract a hair it is necessary to hold the jaws together by finger pressure on the wings and manually move the entire construction of the tweezer bodily rearwardly in a direction away from the hair. In this operation, the tweezer, if adjusted for no rearward stroke of the jaws, is similar in operation to the simple plain tweezer of the type well known in the art which consists merely of two hinged jaws adapted to extract a hair provided it is bodily moved away from the hair.

When the wings of the tweezer according to the forms shown in Figs. 16 and 20 inclusive are rapidly manipulated after the stroke and pressure on the jaws thereof have been adjusted, as desired, it has been found that this adjustment becomes disturbed unless appropriate means is provided to prevent partial and accumulative rotation of the guide sleeve which otherwise would take place. To overcome this difficulty, namely to prevent partial rotation or creepage of the sleeve during the manipulation of the wings, the top wall 90 of the sleeve is provided with a pair of aligned indents or grooves 104 and 105 which cooperates with the depending detents 89 of the squared head 81, the detents and indents interlocking or snapping into position to hold the sleeve against creepage relative to the head 81 of the jaws.

The sleeve 80 may be separated from the head 81 by moving it bodily downwardly away from post 87 and against the action of spring 99 and by shifting the upper part thereof after separation from head 81 to one side it may be removed from the jaws after which both the spring and stud, if desired may be removed or replaced.

In this case of the embodiment illustrated in Fig. 20, the latter in construction is similar to the tweezer in accordance with Figs. 16 to 19 inclusive except that the wings and jaws thereof are interconnected by suitable oblique springs as 106 to provide automatic gradually increasing side pressure to the jaws as their extracting stroke progresses rearwardly.

In the broader aspects of my invention, I do not desire to be understood as limiting its embodiments to details herein shown illustratively as a wide variety of modifications may be made within the scope of the appended claims without departing from the spirit of the invention.

I claim:

1. In a tweezer, the combination of, a pair of hair gripping and extracting jaws, a pair of pivotal wings, links pivotally connected to the jaws and wings, a rotatable guide for slidably housing the upper portion of said jaws, means within the guide for holding the gripping and extracting faces of said jaws apart, and laterally extending spring means interconnecting the jaws and wings to provide side pressure to said faces during retraction thereof.

2. In a tweezer, the combination of, a guide, a pair of hair gripping and extracting jaws having their upper portions slidably disposed in said guide, a member disconnectably seated on said guide, a pair of wings pivoted to said member, links pivotally connected to the jaws and wings, means movable with said jaws and co-

operating with said guide for limiting rearward movement of the jaws, means for normally holding said jaws apart, and means carried by said member for urging said wings laterally.

3. In a tweezer, the combination of, a rotatable guide, a pair of hair gripping and extracting jaws having their upper portions slidably disposed in said guide, a member disconnectably seated on said guide, a pair of wings pivoted to said member, links pivotally connected to the jaws and wings, means controlled by said guide and adjustable relative to said jaws for regulating rearward movement thereof, spring means for holding said jaws apart and the guide against said member and means for normally urging said wings laterally.

4. In a tweezer, the combination of, a rotatable guide, a pair of hair gripping and extracting jaws having their upper portions pivotally and slidably disposed in said guide, a pair of pivotal wings, links pivotally connected to the wings and jaws, spring means within said guide and means adjustable with respect to said jaws and controlled by said guide for regulating the pressure on said spring means.

5. In a tweezer, the combination of, a rotatable guide, a pair of hair gripping and extracting jaws having their upper portions pivotally connected and slidably arranged in said guide, a pair of pivotal wings, links pivoted to the wings and jaws, means cooperating with said guide for adjusting the rearward stroke of said jaws, and means to prevent the disturbance of said adjustment upon the manipulation of said wings.

6. In a tweezer, the combination of, a rotatable guide sleeve, a pair of hair gripping and extracting jaws having their upper portions pivotally connected and slidably arranged in said sleeve, a member disconnectably seated on said sleeve, wings pivoted to said member, spring means carried by said member for urging said wings laterally, links pivoted to said jaws and wings, an adjustable stud mounted on one of said jaws and bodily movable with said sleeve, and means acting on said stud to force the gripping faces of said jaws apart and the sleeve against said member.

7. In a tweezer, the combination of, a rotatable guide sleeve, a pair of hair gripping and extracting jaws having their upper portions pivotally connected and slidably arranged in said sleeve, a member disconnectably seated on said guide sleeve and having an extension projecting therein, wings pivoted to said member, links pivoted to the jaws and wings, spring means for normally urging the wings laterally, an adjustable stud mounted on one of said jaws and bodily movable with said sleeve, spring means acting on said stud to force the lower parts of the jaws apart and the sleeve against said member, the guide sleeve being rotatable about said extension, the distance between said stud and extension being adapted to be varied upon the rotation of said guide sleeve.

8. In a tweezer, the combination of, a rotatable guide sleeve, a pair of hair gripping and extracting jaws having their upper portions pivotally and disconnectably associated and slidably arranged in said sleeve and spaced from the top wall thereof, a member disconnectably seated on said guide sleeve and having a post extending into an opening of said wall, means pivotally associated with said member and jaws for reciprocating said jaws, spring means normally resisting reciprocation of said jaws and abutting

said wall and encircling said post and adjustable means connected to one of said jaws and to said sleeve to control the rearward stroke of said jaws relative to said post.

- 5 9. In a tweezer, the combination of, a guide including opposed sockets, a pair of jaws having the upper portions slidably disposed within said guide, a pair of wings having pivotal connections with said sockets, means within the guide to lock 10 said connections in position and to maintain the gripping and extracting portions of the jaws normally separated, and means interconnecting the jaws and wings for effectively holding the jaws together during the extracting stroke 15 thereof.

10. The device of claim 9 in which the guide takes the form of a hollow cylinder with an external squared end in which end said sockets are provided on opposite sides thereof, the squared 20 end being of such size and shape and the sockets being of such depth that their central portions open within the inside of the cylinder, the lock means comprising a cylindrical slide in said 25 guide, and the pivotal connections include knob shaped projections adapted to be received in said sockets for interlocking with said slide.

11. In a tweezer, the combination of, a pair of side wings, a pair of jaws, a tube within which the upper ends of said jaws slidably extend having 30 transverse sockets adjacent one end thereof, a plug within the tube, said wings having inwardly extending flanges adapted to fit within said sockets, the flanges having portions adapted to straddle said plug and a terminal of said tube having an opening to permit the insertion of a 35 tool to disconnect the plug from the flanges and spring means to create side pressure on said jaws on the rearward stroke of the latter, and means within the tube to hold plug interlocked 40 with said flanges and the gripping and extracting portions of the jaws separated.

12. In a tweezer, the combination of, a pair of side wings, a pair of jaws, a casing within which the inner ends of said jaws slidably extend having 45 opposed sockets adjacent one end thereof, a plug within the casing, said wings having flanges to fit within said sockets, the flanges including means for interlocking with said plug, a spring within the casing acting against the jaws and plug, links pivotally connecting the jaws and wings and spring means acting against the jaws to apply side pressure thereto.

13. In a tweezer, the combination of, a pair of jaws, a casing within which the inner ends of 55 said jaws slidably extend having opposed sockets adjacent one end thereof, a pair of wings pivoted to said casing a plug within the casing, said wings having flanges to fit within said sockets, the flanges including means for removably 60 interlocking with said plug, a spring within the casing acting against the jaws and plug, links pivotally connecting the jaws and wings and spring means interconnecting the jaws and wings for applying a progressively increasing side pressure to said jaws upon their retraction.

14. In a tweezer, the combination of, a guide, a pair of jaws having portions slidably disposed in said guide and other portions projecting therefrom, means for reciprocating said jaws, 70 adjustable means movable with said jaws and controlled by said guide for regulating the rearward stroke of said jaws, and spring means adapted to be compressed or expanded relative to a wall of said guide by said adjustable means.

- 75 15. In a tweezer, the combination of, a rotata-

ble guide, a pair of jaws having a pivotal connection and slidably disposed in said guide and hair extracting portions extending therefrom, means for reciprocating said jaws, adjustable means movable with said jaws and controlled and guarded by said guide for regulating the rearward stroke of said jaws, and spring means normally exerting a force to separate said extracting portions and adapted to be compressed or expanded relative to a wall of said guide by 10 said adjustable means.

16. In a tweezer, the combination of, a pair of hair gripping and extracting jaws, a rotatable guide for slidably housing the upper portions of said jaws, means for reciprocating said 15 jaws, spring means within said guide normally exerting a force to separate the gripping and extracting portions of said jaws and means actuated by said guide and cooperating with said spring means to permit or prevent retraction of said jaws.

17. In a tweezer, the combination of, a rotatable guide, a pair of hair gripping and extracting jaws movably disposed in said guide, spring means within said guide to normally separate the gripping and extracting portions of said 25 jaws, actuating means to reciprocate said jaws, means movable with said guide and adjustable relative to said jaws for adjusting the rearward stroke of said jaws and means to prevent the 30 disturbance of said adjustment upon manipulation of said actuating means.

18. In a tweezer, the combination of, a rotatable guide sleeve, a pair of gripping and extracting jaws having their upper portions pivotally 35 and disconnectably associated and slidably arranged in said sleeve and spaced from the top wall thereof, a member disconnectably seated on said guide sleeve and having a post extending into an opening of said wall; means connected 40 to said member and jaws to reciprocate the latter, adjustable means slidably guided by and movable with said sleeve and having a portion threadably associated with one of said jaws and spring means mounted on said adjustable means 45 normally resisting reciprocation of said jaws and abutting said wall and encircling said post, said spring means normally exerting a force to hold said guide against said member and adapted to be compressed or expanded upon the 50 rotation of said guide.

19. The tweezer according to claim 25 characterized in that said member and guide comprise locking means to prevent disturbance of a set position of said adjustable means during 55 reciprocation of said jaws.

20. In a tweezer, the combination of, a hollow rotatable guide, a pair of jaws having portions slidably disposed in said guide and gripping and extracting portions extending therefrom, means 60 for reciprocating said jaws, adjustable controlled means mounted on one of said jaws adapted upon the selective rotation of said guide to increase or decrease the distance between a terminal thereof and a wall of said guide, and a spring interposed between said wall and terminal adapted to be compressed or expanded 65 upon the rotation of said guide.

21. In a tweezer, the combination of, a hollow sleeve, a pair of jaws having portions slidably disposed in said sleeve and gripping and extracting portions extending therefrom, means for reciprocating said jaws, adjustable means having a portion thereof slidably guided by said sleeve and another part threadably con- 70

nected to one of said jaws and spring means mounted on said portion and abutting a wall of said sleeve, said spring being adapted to be compressed or expanded upon selective rotation 5 of said sleeve to change the force applied to said jaws in accordance with a settable position of said adjustable means.

22. In a tweezer, the combination of, a member, a pair of wings pivotally carried by said member, a hollow guide sleeve rotatably associated with and removably connected to said member, a pair of jaws having portions slidably arranged in said guide sleeve and gripping and extracting portions extending therefrom, links 15 pivotally connected to said jaws and wings, adjustable means having a terminal portion thereof slidably guided by said sleeve and another part threadably connected to one of said jaws, spring means mounted on said terminal portion and abutting a wall of said sleeve to removably retain the latter against said member, said spring means being adapted to be com- 20

pressed or expanded upon selective rotation of said sleeve to change the force applied to said jaws in accordance with a settable position of said adjustable means, and other spring means carried by said member and abutting said wings 5 for normally urging the latter outwardly.

23. The tweezer according to claim 29 in which said member includes detent means co-operating with indent means of said wall to prevent displacement of said adjustable means 10 after a set position thereof during the reciprocation of said jaws upon the manipulation of said wings.

24. In a tweezer, a guide, a pair of jaws 15 slidable relative to said guide, means for reciprocating said jaws, means controlled by said guide to vary the rearward stroke of said jaws or to prevent retraction thereof, and locking means effective upon the reciprocation to said jaws to prevent changing of said rearward 20 stroke.

SAMUEL SEGAL.
